OYSTER-OPENER

Friedrich W. Mittel, Brooklyn, N. Y.

Application June 9, 1932, Serial No. 616,171

7 Claims. (Cl. 17—9)

This invention concerns an opener for bivalves, such as clams, oysters, etc.

The valves of a bivalve are held together by ligaments and the opening of such mollusks requires skill and force, particularly when they are to be opened in quantities.

One object of this invention is to facilitate the opening of the bivalve by the use of a mechanism and levers in the opening operation.

10 A second object of this invention is to provide a platform, on which the bivalve is firmly and alignedly held in opposition to the force applied to a knife for the purpose of separating the valves.

15 I further provide means on a platform for readily adjusting the level of the bivalve—deposited and held on said platform,—with the opening knife, in accordance with the size of said bivalve.

20 Another object of this invention is to provide means in connection with such a platform which facilitates the removal and proper disposal of the juice.

25 Still another object of this invention is mechanically to actuate clam or oyster opening knives in such a manner that they are not only inserted between the shells but are simultaneously or subsequently rotated, whereby the shells are pried apart.

30 A further object of this invention is to permit tilting of the bivalve to be opened at such an angle during the opening operation, that the opening knife does not contact with the mollusk contained between the shells.

35 These and other objects of this invention will be more clearly understood from the following description and appended drawing, in which

Fig. 1 is a partly sectioned top view showing the device of my invention.

40 Fig. 2 shows a corresponding side elevation.

Fig. 3 shows a partly sectioned detail view of the reciprocating knife of my invention.

Figs. 4 and 5 show side and end views of a modified oyster opening knife.

45 Similar numerals refer to similar parts throughout the various views:—

My device comprises a frame 11, which is suitably fastened against a wall or upon a table 12, as indicated in the drawing by means of screws

50 13; the frame 11 comprises a bifurcated bracket 14 with arms 15 and 16, which are provided with a longitudinal bore accommodating the reciprocating arbor 17.

At the front, frame 11 has an extension 18 of 55 the form of a closed loop. Upon opposite sides

of the extension 18 lugs 19 protrude upwardly therefrom. These lugs are transversely bored in coaxial alignment, and they rotatably accommodate the pins 20, which extend from opposite sides of the platform 21. The platform 21 is 5 suitably shaped at its bottom 22 so as to permit bivalves to be placed thereinto; at the same time there is a wall 23 at the back of the platform which serves as a back rest. The back rest takes up the force applied to the oyster by means 10 of the knife 24, which is integral with the sleeve 29 fitting over the front end of arbor 17. The back of the platform 21 rests upon the transverse bar or back stop 25 of extension 18, and it may be lifted from said bar, together with the oyster 15 contained therein, so that the oyster is tilted at the end which faces the knife, and may thus be brought into alignment therewith.

When the platform 21 is tilted to a greater extent from a position on which it rests on the 20 bar 25, the juice of the open bivalve, which rests in said platform, flows out from the bivalve through the opening in the extension 18 into a container 26, which is suitably placed underneath, upon the table 12. The arbor 17 comprises 25 a rod 27, the diameter of which is reduced at one end 28, where it slidably fits into a sleeve 29. The sleeve 29 is closed at one end, from which the knife 24 protrudes.

The receded part 28 of arbor 17 is retained 30 in the sleeve 29, against the pressure of the compression spring 30 in said sleeve, by means of a pin or shoulder screw 31 which extends from the receded part 28 through a guide slot 32 which is helically disposed in sleeve 29. The arbor 17 is 35 normally in the extended position shown in Fig. 3. But when the rod 27 is pushed into the sleeve 29, against the pressure of spring 30, the pin 31 slides along the helical slot 32 of the sleeve, so that the rod and the sleeve are angularly displaced about 40 their common axis in respect to each other.

The pin or shoulder screw 31 extends to such a distance from rod 27 through sleeve 29 that its free end is slidably accommodated in a longitudinal slot 33 extending through the wall of 45 the bore in arm 15. The arbor 17 is therefore non-rotatable, but it is longitudinally reciprocatably supported in the bifurcations 15 and 16 of the frame 11. If the sleeve 29 is prevented from participating in such longitudinal motion of arbor 50 17, the pin 31 sliding along slot 32 causes rotation of said sleeve. The reciprocations are brought about by means of the hand lever 34 which is fulcrumed at 35 upon the arm 16 and which is operatively connected to the rod part 27 by means 55

of a link 36 (shoulder screws 37 and 38). A flat 39 on the side of the rod 27 accommodates the one end of said link 36 in abutment.

The machine is operated as follows: The bivalve 5 is deposited on the platform 21 which is tilted so that the knife 24,--when lever 34 is brought to the front--wedges between the two valves of the bivalve. When the knife 24 has been inserted to such an extent between the valves 10 that it strikes the front end of sleeve 29, which serves as a stop, the movement of said sleeve to the fore is intercepted; further movement of knife feeding rod 27 in a frontward direction causes the spring 30 to be compressed, the sleeve 29 starting 15 to rotate, because the pin or shoulder screw 31 moves along the helical slot 32.

Rotation of sleeve 29 brings about rotation of the knife 24 which is inserted between the valves 20 of the bivalve so that the said valves are pried apart. The tiltable suspension of platform 21 permits the lower valve to be depressed while resting on the platform.

The knife at the front end of sleeve 29 may run 25 more to a point as indicated in connection with the knife 40 of Figs. 4 and 5.

This makes it easier to insert the knife between the valves of the bivalve. The knife 40 may be 30 made accentuatedly blunt at its base 41 because that part thereof is not used for cutting but for 35 prying open the bivalve, during which operation that part of the knife slides along the edges of the valves.

After the bivalve has been opened, its support is tilted so that the juice drains from the lower 35 valve into container 26.

What I claim is:

1. An opener for bivalves, comprising a reciprocatable knife, a back stop, and a platform for bivalves normally supported by said back stop in a position of operative alignment with said knife 40 and tiltable relative to the back stop around an axis substantially normal to the direction of reciprocation of said knife, so that a bivalve de-

posited on said platform may be aligned with said knife by tilting said platform.

2. In an opener for bivalves, a back stop, a platform supporting the bivalve and tiltable from a position substantially against said stop in which the bivalve is opened into a position in which the juice flows out of said bivalve. 5

3. In an opener for bivalves, a platform supporting the bivalve in a position in which the juice flows out of said bivalve when it has been 10 opened, said platform being rotatable in said opener around an axis extending through the bivalve supported by said platform.

4. An opener for bivalves, comprising means supporting a bivalve, a knife movable towards 15 and away from a bivalve supported by said means, a stop on said knife preventing the insertion thereof between the valves of a bivalve beyond a predetermined depth, and means actuated by contact of the valves with said stop and rotating 20 said knife after it has been inserted between said valves up to said stop.

5. An opener for bivalves, comprising means supporting a bivalve, a knife and stop, means for pressing said knife between the valves of said 25 bivalve up to said stop, and means rotating said knife when said stop is pressed with predetermined pressure onto said bivalve.

6. An opener for bivalves, comprising a tiltable platform, a knife movable towards and away from 30 said platform, and a back stop upon which said platform normally rests in a substantially horizontal position and from which it may be tilted toward said knife, the edge of a bivalve deposited on said platform being aligned with said knife 35 by tilting said platform.

7. In an opener for bivalves, a frame, a movable knife mounted in said frame, and a tiltable support for a bivalve mounted in said frame at the level of said knife, so that it faces said knife at 40 various angles between a horizontal and a vertical position.

FRIEDRICH W. MITTEL.
